UNITED STATES PATENT OFFICE.

AUGUST G. LIEBMAN, OF CHICAGO, ILLINOIS.

RAIL-CHAIR.

1,279,724.

Specification of Letters Patent. Patented Sept. 24, 1918.

Application filed April 12, 1915, Serial No. 20,835. Renewed June 13, 1918. Serial No. 239,875.

To all whom it may concern:

Be it known that I, AUGUST G. LIEBMAN, a citizen of the United States, residing at Chicago, in the county of Cook and State of Illinois, have invented certain new and useful Improvements in Rail-Chairs, of which the following is a specification.

This invention relates to railway track appliances and more particularly to rail chairs. 10 The object of the invention generally stated, is to provide means for holding rails under all conditions of track and for use with any type of tie that may be considered most economical from an engineering point 15 of view.

A further purpose of the invention is to provide a rail chair including a bed plate having depending portions or dowels which extend into the tie and constitute in effect 20 abutments for coaction with the rail clamping members.

A further object is to provide a rail chair having a bed plate, the upper surface of which is flat and unobstructed thereby to 25 expedite rail renewals when the rail clamping members are detached.

A further object is to provide a rail chair, the bed plate of which may be permanently attached to the tie in the shop of the treating 30 plant, said bed plate being devoid of surface projections so as to obviate breakage of abutments and the like in rough handling of ties when distributed by being thrown from cars on the right of way.

35 A further object is to provide a rail chair, the rail clamping members of which have an increased range of vertical adjustment without increasing the size or cubic volume of said clamping members.

40 A further object is to provide a primary fastening device or screw bolt which serves the dual function of holding the bed plate to the tie and the rail clamping members to the rails, while at the same time making it 45 possible to keep the bolt tight by adjusting the bolt from the top of the bed plate. When the bolt receiving hole becomes worn the bolt may be removed and a reinforcing sleeve driven into the old bolt hole and the 50 bolt replaced without total disengagement of the fastenings, thereby compensating for bolt wear.

A further object is to form the frusto-

conical rail clamping member with a terminal seating recess adapted to receive a 55 spring washer and thus insure the desired compensation for recoil of the rail under stress and at the same time keep the parts tight.

Further objects and advantages will appear in the following description, it being understood that various changes in the form, proportion and minor details of construction may be resorted to within the scope of the appended claims. 60 65

In the drawings,—

Figure 1 is a perspective view of a rail chair embodying the present invention;

Fig. 2 is an end elevation, one of the rail clamping members and its associated parts 70 being shown in section;

Fig. 3 is a top plan view of Fig. 1, the rail engaging member on one side of the bed plate being detached to show the construction of the abutment in the bed plate, 75 the rail being shown in section, and the bed plate provided with auxiliary screw spike receiving holes;

Fig. 4 is a perspective view of the bed plate shown in Fig. 1 detached, and looking at the under side thereof, one of the 80 dowels being broken away to show the interior construction of said dowels;

Fig. 5 is a perspective view of one of the frusto-conical rail clamping members detached; 85

Fig. 6 is a perspective view of one of the screw cap fastenings detached;

Fig. 7 is a transverse sectional view illustrating a modified form of the invention; 90

Fig. 8 is a perspective view of the bed plate shown in Fig. 7 detached.

Fig. 9 is a detail perspective view of a portion of the bed plate shown in Fig. 7, the plate being provided with a terminal upstanding reinforcing rib to receive the lateral thrust of the adjacent rail clamping member. 95

Corresponding and like parts are referred to in the following description and indicated in all the views of the drawings, by the same reference characters.

Referring to the drawings, A represents a rail having a standard cross section, and B a tie supporting the rail. Mounted upon the 105 cross tie B is a bed plate 5, preferably a mal-

leable casting, although the plate may be otherwise formed if desired. The bed plate 5 is substantially rectangular in shape and preferably extends the entire width of the upper surface of the tie, as shown. Depending from the bed plate 5 and preferably formed integral therewith are extensions or dowels 6 which fit into correspondingly shaped recesses 7 formed in the upper surface of the cross tie. The exterior walls of the dowels 6 are cylindrical while the interior walls of the said dowels are formed with a plurality of flat faces 8, constituting in effect abutments. The upper ends 10 of the dowels open through the upper surface of the bed plate 5 while the lower ends of said dowels are provided with apertures 9 for the reception of primary fastening devices, preferably in the form of 15 screw spikes 19. Each screw spike 10 is provided at its upper end with machine threads 11 terminating in an angular head 12 to permit the screw to be conveniently grasped with a wrench or other suitable tool 20 to effect the adjustment thereof when necessary, the lower end of each spike 10 extending to the lower side of the cross tie and being provided with threads 13 for engagement with a clamping nut 14, which latter is 25 countersunk in the bottom of the tie, as shown. Formed on each spike or fastening device 10 immediately below the machine threads 11 is an annular shoulder 15, the 30 lower face of which is convex for engagement with the correspondingly concave surface of the adjacent extension or dowel 6. Thus it will be seen that the shoulder 15 by engagement with the concave face of the dowel serves as a means for anchoring the 35 bed plate to the cross tie.

As a means for holding the rail A in different positions of lateral and vertical adjustments on the bed plate, there are provided interchangeable rail clamping members 17 each preferably frusto-conical in shape and provided with an eccentric portion 18 adapted to bear against the adjacent longitudinal edge of the base flange of the rail A for shifting the rail laterally with 40 respect to the bed plate when the clamping members are adjusted, said eccentric portion defining a circumferential clamping lip 19 for contact with the upper face of the base flange of the rail. Depending from the eccentric portion 18 of each rail engaging member is a sleeve or extension 20 having a cylindrical bore 21 and a plurality of flat faces 22 corresponding in number to and adapted to bear against the flat faces 8 of the 45 dowels 6. As a means for locking the rail engaging members in contact with the base flange of the rail A there are provided suitable screw caps 23, each provided with a depending cylindrical portion having internal 50 threads for engagement with the machine

threads 11 of the adjacent screw spike 10, the exterior walls of the cylindrical portions of the screw caps being smooth and unobstructed for engagement with the corresponding smooth cylindrical walls 21 of the rail clamping members. The upper end of each screw cap is provided with an angular head 25 to permit the screw cap to be conveniently grasped with a suitable tool, there being an annular flange 26 formed on each screw cap beneath the head 25, as shown. Surrounding the bore 21 of each rail clamping member at the flat face 27 thereof is a seating recess 28 in which is fitted a spring washer 29 of any suitable construction and 75 against which the flange 26 of the adjacent screw cap is adapted to bear, thereby to insure the desired compensation for recoil of the rail under stress and at the same time keep the parts tight. 85

It will here be noted that the rail clamping members 17 are disposed in staggered relation on the bed plate 5 while the screw spikes or bolts 10 not only serve to hold the bed plate on the cross tie but by engagement 90 with the threaded walls of the screw caps serve to lock the rail engaging members in contact with the base flange of the rail. In order to assist in anchoring the bed plate on the cross tie, said bed plate is preferably 95 formed with one or more openings 30 adapted to receive auxiliary screw spikes 31 of any improved construction.

Attention is here called to the fact that by reason of the length of the extensions 20 of the rail clamping members and the disposition of the dowels or abutments with respect to the upper surface of the cross tie, an increased range of vertical adjustment of the rail fastening devices may be effected, without the necessity of materially increasing the size or bulk of said rail fastening devices. 105

In order to adjust the rail laterally on the bed plate for gage it is merely necessary to remove the screw caps 23 and position one of the rail clamping members within the adjacent abutment or dowel with the large portion of the eccentric bearing against the base flange of the rail on one side thereof and with the short portion of the eccentric of 115 the other clamping member bearing against the base flange of the rail on the other side of said rail, after which the screw caps are threaded on the screw spikes and adjusted home, which clamps the members 17 in engagement with the base flange of the rail and effectually prevents accidental displacement of said rail. It will be understood that by moving the rail clamping members 17 to different positions of adjustment within the 120 dowels or abutments, the rail may be shifted laterally in either direction for gage, as required. In order to adjust the rail vertically for surface the screw caps are rotated to elevate the same and a shim 31 placed be- 125 130

neath the rail, after which the screw caps are tightened, as best shown in Fig. 2 of the drawings.

In Figs. 7 and 8 of the drawings there has been illustrated a modified form of the invention in which the bed plate 5' is preferably rolled and the depending extensions or dowels 6 dispensed with. In this form of the device the bed plate 5' is provided with 10 spaced openings 32 preferably disposed in staggered relation to the base flange of the rail and adapted to register with the openings 7' in the tie. The walls of the openings 32 are provided with a plurality of flat 15 faces 33 corresponding in number to and adapted to bear against the flat faces 22 of the extensions of the rail clamping members.

The flat faces 33 of the openings in the bed plate 5' serve the same function as the 20 angular walls of the openings of the dowels 6, that is to say they constitute abutments for engagement with the extensions of the rail clamping members and serve to receive the lateral thrust of said members. When 25 the dowels 6 are dispensed with the bed plate 5' is retained in position on the upper surface of the cross tie by means of screw spikes which pass through suitable openings 34 formed in said bed plate, as best shown 30 in Fig. 8 of the drawings. The construction and operation of the device shown in Fig. 8 is otherwise similar to that shown in Figs. 1 and 2 of the drawings, that is to say the extensions 20 of the rail clamping members 35 pass through the openings 32 in the bed plate 5' and seat in the openings 7' in the tie while the lateral and vertical adjustment of the rail clamping members is effected by manipulating the screw caps as before stated.

40 In Fig. 9 of the drawings there is illustrated a further modification in which the bed plate is roiled or otherwise formed with an upstanding transversely disposed reinforcing rib 35, which bears against the adjacent rail engaging member and serves to reinforce said member and receive the lateral thrust imparted thereto. The height of the reinforcing rib 35 is preferably such as to engage the rail clamping member in the different positions of vertical adjustment of 45 the latter so as to form a reinforcement for the rail engagement member regardless of the adjustment thereof.

From the foregoing description it will be 55 seen that the improved chair provides for gage variations on curves and tangents; for the restoration of gage without respiking and for rail surface variations, low joints, kinks, shimming and the like without re-spiking.

The chair and fastening forming a part thereof is so constructed that it will effectually eliminate mechanical wear to cross ties and, consequently, prolong the life of treated or untreated ties by providing for lateral

and vertical adjustment of the rail for curves or tangents without the necessity of disturbing the primary fastening devices or respiking or shifting the bed plate of the chair on the tie to effect such adjustments.

Having thus described the invention, what is claimed as new is:—

1. A rail chair including a bed plate having openings therein and constituting abutments, and substantially frusto-conical rail 75 clamping members having depending portions fitting within the openings in the bed plate for holding a rail in different positions of lateral and vertical adjustment with respect to the bed plate. 80

2. A rail chair including a bed plate having openings therein, the walls of which are angular, and constitute abutments, and substantially frusto-conical rail clamping members having depending angular portions fitting within and movable to different positions around the angular walls of the openings for holding a rail in different positions of lateral and vertical adjustment with respect to the bed plate. 90

3. A rail chair including a bed plate having openings therein and disposed in staggered relation, the walls of said openings being angular and constituting abutments, and substantially frusto-conical rail clamping members having depending angular portions fitting within and movable to different positions around the angular walls of the openings for holding a rail in different positions of lateral and vertical adjustment with respect to the bed plate. 95

4. A rail chair including a bed plate having openings formed in the opposite ends thereof and disposed in staggered relation to each other, said openings being adapted 105 to register with corresponding openings in a cross tie, primary fastening devices engaging the cross tie, rail clamping members fitting within the openings in the bed plate for holding a rail in lateral and vertical adjustment with respect to the bed plate, and secondary fastening devices engaging the primary fastening devices and said rail clamping members. 110

5. A rail chair including a bed plate having openings formed therein, the walls of which are angular and constitute abutments, primary fastening devices for engagement with a cross tie, rail clamping members having depending angular portions fitting within the openings in the bed plate and movable to different positions with respect to the walls of said openings for holding a rail in lateral and vertical adjustment with respect to the bed plate, and secondary fastening devices engaging the primary fastening devices and bearing against the adjacent rail clamping members. 115 120

6. A rail chair including a flat bed plate having openings arranged at the opposite 130

- ends thereof and disposed in staggered relation to each other, the walls of said openings being angular and constituting abutments, rail clamping members having depending 5 angular portions fitting within the openings in the bed plate for clamping a rail in lateral and vertical adjustment with respect to the bed plate, there being a seating recess formed in each rail clamping member, primary 10 fastening devices, secondary fastening devices engaging the primary fastening devices and rail clamping members, and washers seated within the recesses in the rail clamping members.
- 15 7. A rail chair including a bed plate having spaced openings formed therein and disposed one on each side of the transverse axis of the plate, the walls of said openings being angular and constituting abutments, primary 20 fastening devices for engagement with a cross tie, rail clamping members having eccentric portions for contact with the base flange of a rail and provided with depending angular portions adapted to fit within 25 the adjacent openings of the bed plate, and secondary fastening devices engaging the primary fastening devices and co-acting with the rail clamping members.
8. The combination with a cross tie having 30 spaced recesses formed therein, of a bed plate seated on the cross tie and provided with spaced openings adapted to register with the recesses in the cross tie, the walls of said openings being angular and constituting abutments, a rail resting on the bed plate, primary fastening devices extended through the cross tie at the recesses therein, rail clamping members having angular portions fitting within the openings in the bed 35 plate, secondary fastening devices engaging the primary fastening devices and co-acting with the rail clamping members, and auxiliary fastening devices piercing the bed plate and engaging the cross tie.
- 40 9. A rail chair including a bed plate having depending dowels adapted to fit within a cross tie, the interior walls of said dowels being angular and constituting abutments, rail clamping members having angular portions fitting within the dowels for holding 45 a rail in lateral and vertical adjustment with respect to the bed plate, and means co-acting with the rail clamping members for locking the latter in adjusted position.
- 50 10. A rail chair including a bed plate having spaced openings formed therein, the walls of which are angular and extended downwardly to form dowels for engagement with a cross tie, primary fastening devices having shoulders bearing against the dowels and rail clamping members fitting within 55 and movable to different positions around the dowels for holding a rail in lateral and vertical adjustment with respect to the bed 60 plate, and secondary fastening devices en- 65 gagging the primary fastening devices.
11. A rail chair including a bed plate having spaced openings formed therein, the walls of which constitute abutments and are extended downwardly to form dowels 70 adapted to seat within a cross tie, primary fastening devices having intermediate shoulders bearing against the bases of the dowels and having their upper portions threaded and provided with terminal heads and their 75 lower portions extending through the tie, rail clamping members fitting within the dowels, and secondary fastening devices having threaded portions for engagement with the threads on the primary fastening 80 devices for holding the rail clamping members in adjusted position.
12. A rail chair including a bed plate having depressed abutments, primary fastening devices extending through said abutments, 85 rail clamping members fitting within the abutments and movable to different positions around the same, and secondary fastening devices engaging the primary fastening devices and co-acting with the rail clamping 90 members.
13. A rail chair including a bed plate having spaced depending abutments disposed in staggered relation to each other, the walls of said abutments being angular, primary fas- 95 tening devices for securing the abutments to a cross tie, rail clamping members having angular portions fitting within the abutments, and secondary fastening devices en- 100 gagging the primary fastening devices and forming a housing for the latter.
14. A rail chair including a bed plate having spaced depressed abutments disposed in staggered relation to each other, primary fastening devices extending through the 105 abutments for securing the bed plate to a cross tie, rail clamping members fitting within the abutments for clamping a rail directly on the bed plate or on a shim in different positions of lateral and vertical 110 adjustment with respect to the bed plate, and secondary fastening devices engaging the primary fastening devices and co-acting with the rail clamping members.
15. A rail chair including a bed plate 115 having depending abutments adapted to fit within a cross tie, the inner walls of each abutment being angular and the bottom thereof provided with an opening, primary fastening devices extending through the 120 openings in the abutments and provided with annular shoulders bearing against the bottoms of the abutments, the upper end of each primary fastening device being threaded and the lower end thereof being 125 threaded for engagement with an anchoring nut, rail clamping members having depending angular portions fitting within the abut-

ments, and secondary fastening devices having threaded portions for engagement with the primary fastening devices and provided with laterally extending flanges coöperating with the rail clamping members.

16. A rail chair including a bed plate having spaced depending abutments, primary fastening devices arranged within the abutments for securing the bed plate to a cross tie, rail clamping members having depending portions fitting within the abutments and movable within the abutments to different positions for holding a rail in lateral and vertical adjustment with respect to the bed plate, the upper ends of said rail clamping members being provided with terminal recesses defining flat faces, auxiliary fastening devices engaging the primary fastening devices and having laterally extending flanges extending over the recesses at the flat faces of the rail clamping members, and washers seated in said recesses.

17. A rail chair including a bed plate having openings formed therein and adapted to register with corresponding openings in a cross tie, primary fastening devices engaging the cross tie, rail clamping members fitting within the openings in the bed plate for holding a rail in lateral and vertical adjustment with respect to the bed plate, and secondary fastening devices engaging the primary fastening devices and said rail clamping members.

18. The combination with a cross tie having spaced recesses formed therein, of a bed plate seated on the cross tie and provided with spaced openings registering with the recesses in the cross tie, the walls of said openings being angular and constituting abutments, a rail adapted to rest on the bed plate or on a shim, primary fastening

devices engaging the cross tie at the recesses therein, rail clamping members having angular portions fitting within the openings in the bed plate, and secondary fastening devices engaging the primary fastening devices and coacting with the rail clamping members for holding the rail on said bed plate or shim.

19. A rail chair including a bed plate having depending dowels adapted to fit within a cross tie, the interior walls of said dowels being angular and constituting abutments, and rail clamping members having angular portions fitting within the dowels for holding a rail in different positions of lateral and vertical adjustment with respect to the bed plate.

20. A rail chair including a bed plate having depending dowels adapted to fit within the cross tie, rail clamping members fitting within the dowels for holding a rail in lateral and vertical adjustment with respect to the bed plate, and means coacting with the rail clamping members for locking the latter in adjusted position.

21. A rail chair including a bed plate having openings therein, the walls of which are angular and constitute abutments, and interchangeable substantially frusto-conical rail clamping members having depending angular portions fitting within and movable to different positions around the angular walls of the openings for holding a rail in different positions of lateral and vertical adjustment with respect to the bed plate.

In testimony whereof I affix my signature in presence of two witnesses.
